UNITED STATES PATENT OFFICE.

CYRUS W. BOLSINGER, OF HOMESTEAD, PENNSYLVANIA.

LIQUID COUNTERBALANCE FOR TOOLS.

SPECIFICATION forming part of Letters Patent No. 629,101, dated July 18, 1899.

Application filed January 6, 1899. Serial No. 701,306. (No model.)

To all whom it may concern:

Be it known that I, CYRUS W. BOLSINGER, of Homestead, in the county of Allegheny and State of Pennsylvania, have invented a new and useful Improvement in Liquid Counterbalances for Tools, of which the following is a full, clear, and exact description, reference being had to the accompanying drawings, forming part of this specification, in which—

10 Figure 1 is a front elevation, partly broken away, of a metal-planer constructed in accordance with my invention. Fig. 2 is an end elevation of the same. Fig. 3 is an enlarged front elevation of the cutter-box and support. Fig. 4 is a horizontal section on the line IV IV of Fig. 3, and Fig. 5 is a vertical section on the line V V of Fig. 3.

15

My invention relates to that class of metal-working tools where the strain upon the tool-holder is very heavy; and it is designed to provide an improved counterbalancing device for the tool-holder whereby it may be accurately adjusted to the work and when desired the tool may be easily raised, the 25 weight being taken off the adjusting-screws.

In the drawings, in which I show my invention as applied to a metal-planer, 2 is the vertically-movable cross-slide of a heavy planer, in which the table is indicated by the dotted 30 lines 3. 4 4 are the cutter-boxes, which are supported upon this cross-slide in any desirable manner so as to be moved along it to the desired points. To the base 5 of the cutter-box is secured a block 6 by means of projecting wings 7, which are bolted to the base. 35 Rigidly secured within this block are two vertical cylinders 8 8, containing pistons 9 9, forming part of hollow piston - rods 10 10, which at their upper ends are rigidly secured 40 to the inward projection 11 of the vertically-movable tool-holder 12, which has a dovetail guide connection with the block 6, as shown in Fig. 4.

Fluid-pressure, preferably in the form of compressed air, though oil, water, or other fluid may be used instead thereof, is supplied to the counterbalancing-cylinders by means of flexible hose 13, which lead from a supply-pipe 14 to the upper end of the tool-holder 50 and communicate with passages 15 therein by three-way cocks 16, having exhaust-ports leading to the open air. The supply-pipe 14

is connected to a suitable air-pump 17 by a valved pipe 18, as shown in Fig. 2, this air-pump being located upon any convenient 55 part of the frame.

19 is the adjusting-screw, which extends through the upper end of the block 6, passes through a screw - threaded hole in the inwardly-projecting part 11 of the tool-holder, 60 and has a stepped lower bearing in a flanged plate 20, as shown in Fig. 3. The central portion of the block 6 is suitably cut away to receive the screw, and with a bevel-wheel 21 upon the lower end of the screw-shaft 65 engages the bevel-wheel 22 upon a short counter-shaft extending through the block 6 and having at its rear end a bevel-gear connection 23 with a shaft 24, which extends through the cross-slide and by means of which the tool 70 may be raised and lowered.

The operation is as follows: When it is desired to raise the tool and holder, pressure is supplied to the cylinders in the cutter-boxes sufficient to more than counterbalance the 75 weight of the tool-holder and tools and that part of the cutter-holder engaging the screw is lifted off the screw-threads, so that the screw may be easily rotated to lift the tools. In lowering the tools the pressure is exhausted from 80 the cylinders by opening the three-way valve 16, and the screws may be then rotated either by hand or by the shaft 23, so as to allow the tools to descend. When the tool and holder are lowered to the desired point and are exactly 85 counterbalanced or a little more than counterbalanced, they are held in working position thereby, so that too deep a cut cannot be made.

The advantages of my invention will be 90 apparent to those skilled in the art since the fluid counterbalance is much more simple and effective and more easily regulated than the old counterweights which have been employed. The fluid exerts a constant lifting 95 pressure upon the tool, so as to take up any backlash in the feed-screw, thus giving a much finer adjustment than before, while the tool-holder works more freely and the amount of power necessary to operate the feed is reduced to a minimum. The liquid-pressure 100 may be increased or decreased at will, and by increasing the pressure slightly the screw-holders may be lifted to their starting posi-

tion by a very small amount of power. When applied to drill-presses, the device takes up the backlash of the drill-spindle and prevents the breaking of the drill-point as it is about 5 to go through the work.

The device may be used in connection with drill-presses, boring-mills, or other metal-working tools having vertical adjustment, and many variations may be made in the form 10 and arrangement of the fluid counterbalance and the fluid used therein without departing from my invention, since

I claim—

1. In metal-working tools, the combination 15 with a vertically-adjustable tool, of a fluid-counterbalance device connected thereto and arranged to exert a constant lifting pressure upon the tool during its operation; substantially as described.
2. In metal-working tools, the combination 20 with a vertically-movable cutter-holder, of a counterbalancing fluid-cylinder connected thereto and arranged to exert a constant lifting pressure during the operation of the tool, 25 and a fluid-supply pipe leading to the cylinder; substantially as described.
3. In metal-working tools, the combination

with a cross-slide having a cutter-box containing a vertically-movable tool-holder, of a fluid counterbalancing-cylinder connected to 30 the tool-holder and arranged to exert a constant lifting pressure thereon during the operation of the tool; substantially as described.

4. In metal-working tools, the combination with a support having a fixed cylinder, of a 35 tool-holder secured to the piston-rod of the cylinder, and a fluid-supply pipe leading to the cylinder below the piston-head and arranged to admit a constant pressure during the operation of the tool; substantially as de- 40 scribed.

5. In metal-working tools, the combination with a cutter-box containing fluid counter-balancing-cylinders, of a cutter-holder having its upper ends connected to the piston- 45 rods of said cylinders, and means for constantly supplying fluid under pressure to the cylinders; substantially as described.

In testimony whereof I have hereunto set my hand.

CYRUS W. BOLSINGER.
